UNITED STATES PATENT OFFICE

2,609,629

BADGE

John R. Hubbard, Yellow Springs, Ohio, assignor
to Antioch Bookplate Company, Yellow Springs,
Ohio, a corporation of Ohio

Application December 5, 1949, Serial No. 131,239

5 Claims. (CL. 40—1.5)

1

This invention relates to improvements in markers or tags. More particularly, it relates to tongued badges having a multiplicity of uses. Still more particularly, it relates to convention badges.

Badges must be readily attachable and detachable, and at the same time be capable of gripping with sufficient firmness and tenacity to insure against accidental dislodgment and loss. Further, the badges must be capable of being written upon.

A principal object of the invention, therefore, is to provide an improved badge or tag possessing the above characteristics and which is further characterized by extreme simplicity of form and cheapness of manufacture.

It is a further object to provide a badge of design whereby either the flap or the badge proper may be the face adapted for viewing.

It is a further object to provide a badge capable of attachment against accidental loss in a variety of ways.

The invention resides further in the novel structural details and forms illustrated in the attached drawing in which:

Figures 1, 2 and 3 are face views of several different forms of tags made in accordance with my invention;

Figure 4 is a fragmentary face view showing a pin as securing means;

Figures 5 and 6 show methods of attaching badges so that they are prominently displayed; and

Figure 7 shows the use of the badge as a bookmarker.

With reference to Figures 1 and 2 of the drawing, the tag therein illustrated consists of a flat body member 10 which may suitably be made of cardboard, or suitable plastic material such as phenol-formaldehyde resin, vinyl acetate polymers, phthalic acid base resins, and like materials.

Said body member 10 is provided towards its upper end with apertures 11 and 12 connected by a slot 13 which defines the free edges of a tab 14. 45

It will be noted that in Figures 1 and 2 the slot 13 is comprised of a horizontally extending portion and two vertically extending portions which vertically extending portions each terminate in one of the apertures 11—12.

In the absence of a pocket the tag as shown in Figure 4 may be pinned to the cloth. Under these circumstances, one leg 15 of a safety pin 16 passes from the rear of body member 10 through aperture 12 across the top of tab 14, and 55

to the back of body 10 through aperture 11. With the leg 17 of the pin 16 passed through the cloth and the two legs locked together, the badge is tightly secured.

However, pinning is merely an expedient in the absence of pockets. Normally the badge is worn on a pocket with either the body member 10 or the tab 14 or both portions exposed.

In the embodiment of the invention shown in Figure 5, the badge of Figure 1 is shown attached to a pocket button by means of slit 18 and aperture 19 in the central top portion of the badge.

The preferred mode of attachment and the one for which the badge has several specially designed features is shown in Figure 6 with relation to the badge of Figure 2. In this embodiment of the invention, the badge member 10 is shown within the pocket with the tab 14 in front of the pocket.

The badge grips the fabric with sufficient firmness to withstand any normal disengaging force because of the two upwardly extending tips 20 and 21. It will be noted that the tip 20 is formed by the intersection of the vertically extending edge of the tab 14 with the upwardly extending edge defining the aperture 12, and that similarly the tip 21 is formed by a vertically extending edge bordering the slot and an upwardly extending edge bordering aperture 11. These tips 20 and 21 serve the same useful purpose when the tab 14 is inside as well as outside the pocket.

While the dimensions of the apertures 11 and 12 and slot 13 and of the tab 14 may vary without departure from the invention, it has been found that for general purposes dimensions of all parts corresponding to those in Figures 1, 2 and 3 which are shown in actual size will be found suitable.

The faces of the badges are intended to be written upon in either pencil or ink and if prepared from resin material may be erasable.

The use of the erasable badge of Figure 3 as a bookmark is illustrated in Figure 7. In this figure tab 14 is illustrated as behind a leaf of a book 30 with the body member 10 in front of the leaf.

It will be understood that this invention is susceptible to modification in order to adapt it to different usages and conditions and, accordingly, it is desired to comprehend such modifications within this invention as may fall within the scope of the appended claims.

I claim:

1. A badge comprising a body of sheet material having therein a tab having free edges thereof defined by a pair of upper opposed apertures

3

and a slot joining the apertures, said tab being joined to said body only along an upper line between the said apertures, an edge defining a said slot and an edge defining a said aperture each extending upwardly to an intersection thereof and terminating in an upwardly extended pointed tip.

2. A badge comprising a body of sheet material having therein a quadrilateral tab having the free edges thereof defined by a pair of upper opposed apertures and a slot joining the apertures, said tab being joined to said body only along an upper line between the said apertures, a lateral edge defining a said slot and an upper edge defining a said aperture each extending upwardly to an intersection thereof and terminating into an upwardly extended pointed tip.

3. A badge comprising a body of sheet material having therein a tab having five free edges thereof defined by a pair of upper opposed apertures and a continuous slot having vertical and horizontal portions joining the apertures, said tab being joined to said body only along an upper line between the said apertures, a free edge defining a vertically extending slot portion and a free edge defining a said aperture, each extending upwardly to an intersection thereof and terminating in an upwardly extended pointed tip.

4. In a badge comprising a body of sheet material having a tab joined to the body along the line between a pair of opposed apertures which

together with a slot connecting the apertures define the free edges of the said tab, the structure comprising an upwardly extended pointed tip portion of said tab formed by the terminal intersections of an upwardly extending edge bordering a said slot and an upwardly extending edge bordering a said aperture.

5. In a badge comprising a body of sheet material having a quadrilateral tab joined to the body only along the line between a pair of opposed inwardly disposed apertures which together with a slot connecting the apertures define the free edges of the said tab, the structure comprising a substantially vertically extending tip portion of said tab formed by the intersection of a vertically extending edge bordering a said slot and an upwardly extending edge bordering said aperture.

JOHN R. HUBBARD.
